LEONARD MILLER, OF PRESTWICH, AND LAWRENCE BOOTHMAN, OF STRETFORD, ENGLAND, ASSIGNORS TO WESTINGHOUSE ELECTRIC AND MANUFACTURING COMPANY, A CORPORATION OF PENNSYLVANIA.

ELECTRIC REGULATING-SWITCH.

1,231,632.

Specification of Letters Patent.

Patented July 3, 1917.

Application filed March 3, 1914. Serial No. 822,181.

To all whom it may concern:

Be it known that we, LEONARD MILLER, a subject of the King of Great Britain, and a resident of Prestwich, in the county of 5 Lancaster, England, and LAWRENCE BOOTHMAN, a subject of the King of Great Britain, and a resident of Stretford, in the county of Lancaster, England, have invented a new and useful Improvement in Electric Regulating-Switches, of which the following is a specification.

Our invention relates to electric regulating switches, and particularly to regulating switches by means of which variations in 15 the amount of resistance or of windings in circuit are effected in a large number of steps and by a very small amount at a time.

The object of our invention is to provide an improved construction of regulating 20 switch of this kind which is compact, strong, simple and cheap to build and particularly adapted to the services for which it is intended.

The regulating switch is of that type in 25 which two switching devices are employed, one operating in connecting with what may be termed the main rheostat to vary the resistance by a series of steps and the other operating in connection with what may be 30 called the auxiliary or sub-divided rheostat which is cut into and out of circuit between successive steps on the main rheostat.

In a regulating switch constructed in accordance with our invention, the whole of 35 the resistance of the sub-divided rheostat is substantially equal in amount to one unit or step of the resistance of the main rheostat, but the resistance of the sub-divided rheostat is subdivided into a number of 40 smaller steps by means of taps connected to a series of annularly arranged contact plates over which a switch member is moved by means of a rotary handle or crank which may be operated either manually or by 45 power. The steps of resistance are successively cut out as the switch member is moved over the contact plates by the rotary handle or crank and, when the switch member makes contact with the last contact plate of 50 the series, the whole of the resistance is cut out. Further rotation of the rotary handle or crank of the sub-divided rheostat causes the switch member to move from the last to the first contact plate to again cut 55 all the resistance into the circuit.

The main rheostat has a switch member adapted to move over a series of contact plates that are connected by taps to a corresponding series of resistor units and these contact plates may be either rectilinearly 60 or annularly arranged. Suitable gearing (toothed wheel, pin wheel, screw, etc.) is provided for operating the movable switch member of the main rheostat and a mechanical connection between the said gearing and the rotary handle or crank or the subdivided rheostat. This mechanical connection (which may take any suitable form, such as a lever, cam, pawl or the like) is intermittently brought into and out of operation at one or more predetermined points 65 in each revolution of the handle or crank of the sub-divided rheostat in such manner that the switch member of the main rheostat is moved to cut out one unit or step of 70 resistance at the same time that all the resistance of the sub-divided rheostat is cut in, or vice versa.

In order that our invention may be clearly understood, several ways in which the same 80 may be carried into practice will now be described with reference to the accompanying drawings, in which:

Figure 1 is a front elevation of a regulating switch constructed according to our invention, in which the main rheostat has rectilinearly arranged contact pieces, the electrical connections being illustrated diagrammatically. Fig. 2 is a side elevation of the regulating switch shown in Fig. 1: 85 Fig. 3 is a plan view of a modification in which the main rheostat has annularly arranged contact pieces: Fig. 4 is a side view, partially in elevation and partially in section, of the regulating switch shown in Fig. 90 Fig. 5 is a diagrammatic view of the electric connections of the regulating switch shown in Figs. 3 and 4: Fig. 6 is a view, similar to Fig. 1, of a second modification in which the main rheostat has rectilinearly 95 arranged contact pieces: Fig. 7 is a side view, partially in elevation and partially in section, of the regulating switch shown in Fig. 6.

Referring to Figs. 1 and 2 of the drawings, a form of regulating switch is shown therein comprising a sub-divided rheostat 1 and a main rheostat 2, the latter having rectilinearly arranged contact members and having also terminals 3 and 4 for connecting 105

the regulating switch in the circuit to be regulated. To the terminal 3 are connected a number of resistor units 5¹ to 5¹⁸, inclusive, which are connected by a conductor 7 to one end of a resistor 6 of the sub-divided rheostat 1, the other end of which resistor is connected by a conductor 8 to the other terminal 4 of the main rheostat 2. The resistor 6 of the sub-divided rheostat 1 is made substantially equal in amount to one resistor unit 5 of the main rheostat 2 and is sub-divided into several small steps, shown in the drawing as being ten in number, and indicated at 6¹ to 6¹⁰, inclusive.

15 The resistor steps 6¹ to 6¹⁰ of the sub-divided rheostat 1 are respectively connected, as shown in Fig. 1, to a series of contact plates 9¹ to 9¹², inclusive, which are arranged in a circle to enable a two-arm movable switch member 10 to be moved over them by means of a hand wheel 11 (Fig. 2) mounted upon a shaft 12 which also carries the said movable switch member 10. The contact plates 9¹ to 9¹² are so arranged that, 20 as the switch member 10 is rotated from the position shown in a clockwise direction, the right hand arm of the said switch member makes contact with the contact plate 9⁵ a short time before the left hand arm reaches 25 the contact plate 9⁸, while the left hand arm bridges the contact plates 9⁷ and 9⁸ when the right hand arm rests fully upon contact plate 9⁵ alone, and so on.

30 The resistor units 5 of the main rheostat 2 are connected, in the manner shown, to a number of contact plates 13¹ to 13¹⁸ which are rectilinearly arranged in two parallel rows to enable a two-arm movable switch member 14 to be moved successively over 35 them to cut the said resistor units out of and into the circuit to be regulated. The switch member 14 of the main rheostat 2 is supported by a carrier member 15 from which it is insulated by a member 16 of any suitable material, the carrier member 15 being 40 connected by webs 17 and 18 (Fig. 2) to a sleeve 19. The interior of the sleeve 19 is provided with a quick-traverse screw thread which engages a spiral groove 20 formed in 45 a shaft 21, the upper and lower ends of which are supported, as shown, by suitable bearings 22 and 23. The groove 20 in the shaft 21 is given the same angle of pitch as the screw thread of the sleeve 19, this pitch angle being such that one-eighth of a revolution of the shaft 21 causes the switch member 14 to move forwardly, or backwardly, a distance equal to half the width of one of the contact plates 13¹ to 13⁸, or 13¹¹ to 13¹⁸. 50 The upper contact plate 13⁹ of the left hand row of the contact plates of the main rheostat 2 shown in Fig. 1 is given a width that is greater than the width of the upper contact plate 13¹⁰ of the right hand row by a 55 space equal to half the width of one of the

other contact plates 13¹ to 13⁸ or 13¹¹ to 13¹⁸. In the initial position of the switch member 14, with all the resistor units 5 included in the circuit to be regulated, the lower edge of the right hand arm of the 70 said switch member 14 is substantially in alinement with the lower edge of the contact plate 13¹⁰, so that, when the switch member 14 moves one step forwardly, the lower edge of the left hand arm then comes substantially into alinement with the lower edge of the contact plate 13⁹, while the right hand arm of the said switch member then connects the two contact plates 13¹⁰ and 13¹¹. Upon the switch member 14 being moved 75 another step forwardly, the left hand arm connects the two contact plates 13⁸ and 13⁹ and the right hand arm rests fully upon the contact plate 13¹¹. As the switch member continues to be moved forwardly, one step 80 at a time, it will be seen that, when the left hand arm of the same bridges two successive contact plates 13 of the left hand series of contact plates, the right hand arm rests fully 85 upon one contact plate 13, of the right hand series, also that, when the right hand arm bridges two successive contact plates of the right hand series, the left hand arm rests fully 90 upon one contact plate of the left hand series.

95 By means of the above described staggered arrangement of contact plates of the two rheostats relatively to the respective moving switch members 14 and 10, the latter are enabled to cut one unit of the resistor 5 or one step of the resistor 6 out or in by a comparatively small movement, without involving any undue reduction in the size of the contact plates or in the solidity of the construction generally.

100 As shown in Fig. 1, the left hand arm of the switch member 14 bridges the two contact plates 13⁶ and 13⁷ while the right hand arm rests fully upon contact plate 13¹³. Upon the switch member 14 being moved 105 forwardly into this position by rotating the shaft 21, the resistor unit 5⁷ is cut out of circuit. For the purpose of intermittently rotating the shaft 21 through an angle of 45° according to this invention, the following arrangement is provided:—A pin wheel 24, 110 which is fixed upon the upper end of the shaft 21, is provided upon its periphery, with eight pins or the like 25 which are spaced equal distances apart. The arrangement of the shaft 21 and bearings 22, 23 is such that the pin wheel 24 is conveniently 115 near to the operating shaft 12 of the sub-divided rheostat 1. In the preferred arrangement, the axes of the operating shafts 21 and 12 of the main and sub-divided rheostats, respectively, are arranged in the same plane but at right angles to one another. A lever 26, which is fixed upon the shaft 12 of the sub-divided rheostat, comprises two arms 120

27 and 28 arranged preferably at 180° apart and of such length that, as shaft 12 is rotated by the hand wheel 11, each arm 27 and 28 successively engages a pin 25 of the pin wheel 24. The shaft 21 is thus rotated through an angle of 45° twice in each revolution of the shaft 12. The lever 26 is arranged on the shaft 12 in such relation to the two-arm switch member 10 of the sub-divided rheostat that the arm 27 or 28 of the lever 26 engages a pin 25 of the pin wheel 24 and rotates the shaft 21 through an angle of 45° as the switch member 10 is moving from the last to the first contact plate, that is, 15 from the position in which all the resistor 6 is cut out to the position in which all the said resistor is again cut in.

As shown in Fig. 1, all of the resistor 6 is in circuit. The resistor 6 is gradually cut 20 out by rotating the switch member 10 in a clockwise direction to connect the contact plates 9¹ and 9² when all the resistor 6 is cut out. The whole of the resistor 6 is again cut in when the switch member 10 25 is moved into the position in which it is shown in Fig. 1, in which position it connects the contact plates 9⁶ and 9⁷. Supposing that this movement of the switch member 10 has just been made, it will be seen 30 that thereby the arm 28 has engaged the pin 25² to move the pin wheel 24 and the shaft 21 through an angle of 45° , thus causing the switch member 14 of the main rheostat 2 to move forwardly to cut out one unit of the 35 resistor 5 at the same instant that all the resistance of the sub-divided rheostat 1 was cut in, as described above. It will be observed that, by this movement of the pin wheel 24, the pin 25¹ has been brought into 40 position to be engaged by the arm 27 when the shaft 12 has been rotated through an angle of 180° to cut all the resistor 6 out of, and again into, the circuit.

In order to impart a quick and well defined movement to the shaft 21 and switch member 14 of the main rheostat 2, any suitable known device may be employed, for instance, as shown, a notched disk or the like 45 may be fixed upon the shaft 21 to co-act 50 with a roller 30 that is journaled in a lever 31. The lever 31 is capable of rotating about a fixed pivot 32 and is acted upon by a spring 33 which continuously presses the roller 30 into engagement with the disk 29. 55 This being a well known device which is often employed for a similar purpose, the operation of the same does not require any further description.

The operation of the regulating switch 60 described above is as follows:—The terminals 3 and 4 of the main rheostat 2 are connected across the supply circuit in series with the apparatus, such for example as the field winding of an electric generator (not 65 shown), the current supplied to which is to

be regulated. When the switch member 14 of the main rheostat 2 is in its uppermost position connecting contact plate 13⁹ with contact plate 13¹⁰, and the switch member 10 of the sub-divided rheostat 1 is, in the position shown, connecting contact plates 9⁶ and 9⁷, all the resistors 5 and 6 of the respective rheostats 2 and 1 are connected in circuit in series, and the current traversing the circuit is a minimum. To cut resistance out of the circuit by a large number of very small steps so as to gradually increase the current, the operator, by means of the hand wheel 11, slowly rotates the switch member 10 of the sub-divided rheostat 1, together with the lever 26, in a clockwise direction. As soon as the right hand arm of the switch member 10 of the sub-divided rheostat bridges the contact plates 9⁶ and 9⁵, the step 6⁵ of the resistor of the sub-divided rheostat is cut out, 70 the path of the current being as follows: from terminal 3, through connecting wire 33 to the first contact plate 13¹, through the left hand series of resistor units 5¹ to 5⁹, of the main rheostat 2, through the switch 75 member 14 and connecting wire 34, in parallel, to the upper contact plate 13¹⁰ of the right hand series of contact plates, through the right hand series of resistor units 5¹⁰ to 5¹⁸ of the main rheostat 2, conductor 7, resistor steps 6¹, 6², 6³, 6⁴, contact plate 9⁵ of the sub-divided rheostat 1, switch member 10, contact plate 9⁷, resistor steps 6⁶ to 6¹⁰, 80 and through conductor 8 and terminal 4 to the field winding of the generator to be regulated. As the operator continues to rotate the hand wheel 11 and switch member 10 of the sub-divided rheostat 1, the resistor steps of the latter 6⁶, 6⁷, 6⁸, 6⁹, 6², 6⁹, 6¹, and finally step 6¹⁰ are successively cut out. The 85 current now passes through the whole of the resistor 5 of the main rheostat 2 and thence, by conductor 7, switch member 10 of the sub-divided rheostat 1, conductor 8 and terminal 4, direct to the field winding of the 90 generator to be regulated. 100

As the switch member 10 of the sub-divided rheostat 1 is further rotated from the position in which all the resistance 6 is cut out, the arm 27 of the lever 26 connected 105 to the said switch member engages the pin 25¹ of the pin wheel 24 and moves this pin into the position occupied by the pin 25², as shown in Fig. 1 of the drawing, and at the same time, moving the pin 25⁸ into the 110 position vacated by the pin 25¹. The pin wheel 24 and the shaft 21 are thus rotated through an angle of 45° causing the switch member 14 of the main rheostat 2 to move forwardly (that is, downwardly as illustrated) a distance substantially equal to half the width of contact plate 13¹¹. In this position of the switch member 14, the right hand arm of the same bridges the contact plates 13¹⁰ and 13¹¹, and the left hand arm 130

of the said switch member remains fully in contact with the contact plate 13⁹, so that current now flows directly from the contact plate 13⁹ to the contact plate 13¹¹, and the 5 resistor unit 5¹⁰ is cut out of circuit.

Owing to the position of the arms 27 and 28 of the lever 26 relatively to the switch member 10 of the sub-divided rheostat 1, the above described movement of the switch 10 member 14 of the main rheostat 2 takes place at the same time that the switch member 10 moves from the position in which it connects the contact plates 9¹ and 9² into the position in which it connects the contact plates 9⁶ and 15 9⁷, that is, the resistor unit 5¹⁰ of the main rheostat 2 is cut out at the same time that all the resistor 6 of the sub-divided rheostat 1 is again cut into the circuit. By continuing to rotate the switch member 10 and 20 lever 26 of the sub-divided rheostat 1, the operator proceeds to again successively cut out the resistor sections 6¹ to 6¹⁰ in the order mentioned above until the arm 28 of the lever 26 engages the pin 25⁸ which, as 25 stated above, is now supposed to occupy the position in which pin 25¹ is shown in Fig. 1. Thus, the pin wheel 24 and shaft 21 are again rotated through an angle of 45°, and the switch member 14 of the main rheostat 30 2 is moved forwardly another step to cause the right hand arm of the said switch member to rest fully upon the contact plate 13¹¹ and the left hand arm of the same to bridge the contact plates 13⁸ and 13⁹. In this position of the switch member 14, the resistor unit 5⁹ of the left hand series of the main rheostat 2 is cut out. At the same time, the switch member 10 of the sub-divided rheostat 1 is moved into the position shown in 35 Fig. 1 in which the entire resistor 6 is again cut into the circuit. The above described operation may be continued, if found desirable, until the whole of the resistance of the main rheostat is cut out, that is, until the 40 switch member 14 of the main rheostat 2 directly connects together the first and last contact plates 13¹ and 13¹⁸, respectively.

In Figs. 3 to 5 of the drawings, the invention is illustrated as applied to a main 45 rheostat of the annular type, the contact plates and switch member of which are arranged concentrically with those of the sub-divided rheostat. Referring to these figures, the contact plates 9, twelve in number, of 50 the sub-divided rheostat 1 are shown arranged upon the circumference of the small circle, while the contact plates 13, twenty-seven in number, are arranged upon the circumference of the large circle, both sets of 55 contact plates being secured upon an insulating base plate 35 (Fig. 4). The resistor steps 6 of the sub-divided rheostat and the resistor units 5 of the main rheostat are connected by taps to their respective contact 60 plates 9 and 13 and in series with one an- 65

other, as is clearly shown in the diagram of connections of Fig. 5. The switch member 10¹ of the sub-divided rheostat 1 consists, in this case, of a single brush of laminated copper, or of other good conducting 70 material in a sufficiently flexible form, that is clamped to a sleeve 36 by a screw 37. The sleeve 36, which rests upon a step bearing 38 that is secured upon the insulating base plate 35, is secured by a pin, or the like, 75 39 to a shaft 40 with which also the said sleeve may be electrically connected. To the upper end of the shaft 40, but insulated therefrom, is fixed, for instance, by a pin 41, an operating lever 42 which is rotated 80 by means of a handle 43 of suitable insulating material. The switch member 14 of the main rheostat 2 also consists of a single brush of a suitably flexible good conducting material, such as laminated copper, and is 85 clamped to a metallic carrier 44 which is connected mechanically and electrically to the lower face of a stepped wheel 45. The wheel 45 comprises a central hub 46 that is arranged concentrically with, but loosely 90 upon, the operating shaft 40 of the sub-divided rheostat. The hub 46 of the stepped wheel 45 may, if desired, have a sufficiently close fit upon the shaft 40 to be in electrical connection therewith, but these parts are 95 preferably insulated from the operating lever 42, as will be readily understood. The stepped wheel 45 is supported upon the hub 47 of a notched disk or star wheel 48 which is fixed upon the insulating base plate 35 100 by means of the lugs 49 and 50. The star wheel 48 coacts with a spring pressed roller 51, journaled in a bifurcated support 52 that is arranged to slide within the metallic carrier 44, to hold the stepped wheel 45 correctly 105 in each of its operative positions in which the switch member 14 of the main rheostat 2 rests upon one of the contact plates 13.

In order to intermittently rotate the 110 stepped wheel 45 at the proper time and thus to move the switch member 14¹ of the main rheostat 2 to cut out a resistor unit 5, a pawl 53 is pivoted upon the end of the operating lever 42 and is provided with a 115 projection or tooth 54 adapted to engage the teeth of the stepped wheel 45. For the purpose of holding the tooth 54 of the pawl 53 out of engagement with the stepped wheel 45, a depending projection 55, which is provided upon the pawl 53, is adapted to engage a guard ring 56 that is fixed upon the base plate 35 concentrically with the operating shaft 40 of the regulating switch. A gap 57 (Fig. 3), which is formed in this 120 guard ring, is so located and is of such a width that the tooth 54 of the pawl 53 can be brought by a spring 71, or by gravity, or by both, into engagement with the stepped wheel 45 to rotate it through a sufficient 125 130

- angle to move the switch member 14¹ of the main rheostat 2 from one contact plate 13 to another. The movement of the switch member 14¹ operates to cut a resistor unit 5 out of the circuit at the same time that the switch member 10¹ of the subdivided rheostat 1¹ is moved from the last to the first contact plate 9 to cut all the resistor 6 into the circuit.
- 10 In the operation of this form of the improved regulating switch, the switch member 14¹ of the main rheostat 2¹ is moved only once in each complete revolution of the switch member 10¹ of the sub-divided rheostat 1¹, and a step of resistance of each rheostat is cut out, or in, by the corresponding switch member being moved completely off one contact plate so as to rest fully upon the next succeeding contact plate. In other respects, 20 the electrical operation of this form of regulating switch is similar to that described in detail above in connection with the construction illustrated in Figs. 1 and 2, as will be readily understood with the aid of the 25 diagram of connections of Fig. 5.
- Figs. 6 and 7 show a second modification of our invention in which a main rheostat having rectilinearly arranged contact members is employed, the switch member of 30 which is actuated by means of a stepped wheel and pawls similar to those shown in Figs. 3 and 4. Referring to Figs. 6 and 7, it will be seen that the two-arm switch member 10 of the sub-divided rheostat 1¹¹ moves 35 over a series of contact plates 9 which are connected to the resistor steps 6 and this movement of the switch member 10 successively cuts out each of these resistor steps until the switch member reaches the position 40 in which it is shown in Fig. 6, in which all the resistor 6 is cut out of the circuit. The switch member 14 of the main rheostat 2 moves over the contact plates 13 to cut in, or out, the resistor units 5 of this rheostat, 45 substantially as in the construction shown in Figs. 1 and 2, but, in the present modification, the switch member 14 is loosely mounted upon and guided by a rod 70 upon which it slides. Referring more particularly to 50 Fig. 7, a hand wheel 11 is fixed upon a shaft 58 which also carries the two-arm switch member 10 of the sub-divided rheostat 1 and a two-arm lever 26 having arms 27 and 28. The stepped wheel 45 is loosely mounted 55 upon the shaft 58, and, upon the hub of this wheel, is mounted a stud wheel 59 which contacts with a perforated steel band 60. The steel band 60 also passes over an idle stud wheel 61 (Fig. 6), the spindle 62 of which 60 is mounted in any convenient manner upon a fixed bearing 63 (Fig. 7) and is arranged clear of the contact pieces of the main rheostat 2¹¹. The switch member 14 of the main rheostat 2¹¹ is connected to one side of the steel band 60 (the left side as shown in Fig. 6) so that the said switch member is moved along the guide rod 70 as the stud wheel 59 is rotated.
- A pawl 64, which is pivoted at the outer end of the arm 27 of the lever 26, is provided 70 with a projection or tooth 65 adapted under the action of a spring or gravity or both, to engage the stepped wheel 45 when the lever 26 is rotated into such a position that the lateral projection 66 of the pawl 64 is able 75 to enter the gap 57 formed in the guard ring 56. The mechanical connection and operation of these parts are similar to those described above in connection with the construction shown in Figs. 3 and 4. A similar 80 pawl 67 is pivoted at the outer end of the arm 28 of the lever 26 and is provided with a projection or tooth 68 for engaging the stepped wheel 45, and with a lateral projection 69 for engaging the guard ring 56. 85 By rotating the hand wheel 11 in a counter-clockwise direction, the switch member 10 of the sub-divided rheostat 1 is first moved from its position indicated in Fig. 6 to cut all the resistor 6 into the circuit and this 90 resistor is then gradually cut out during one half of a revolution of the hand wheel 11 and shaft 58. The gap 57 in the guard ring 56 is so arranged that the pawls 64 and 67 severally engage the stepped wheel 45 once 95 in each revolution of the shaft 58 and rotate the stud wheel 59 to move the left hand portion of the steel band 60 and switch member 14 downwardly such a distance that one resistor unit 5 of the main rheostat 2 is cut 100 out of the circuit. It will be seen that, with this construction, as with that shown in Figs. 1 and 2, the resistor 6 of the sub-divided rheostat 1 is alternately cut into and 105 out of circuit twice in each revolution of the operating shaft 58 or of the shaft 12, as the case may be, and that, when all the resistor 6 is cut in, one resistor unit 5 of the main rheostat 2 is simultaneously cut out of 110 the circuit.
- The operation of the invention as described above relates more particularly to cutting resistance out of the circuit to be regulated, but it will be readily understood without further description that resistance 115 may also be cut into the circuit by means of the improved regulating switch by rotating the operating handle or crank of the subdivided rheostat in the opposite direction to that described above.
- While we have shown and described our invention as applied to rheostats, it is understood that this use is illustrative only, and that our invention may be applied equally as well to induction regulators, or similar 125 devices.
- It is evident that various other modifications may be made in the construction and

arrangement of the parts of this improved regulating switch without departing from the scope of the invention.

We claim as our invention:

- 5 1. In an electric regulating switch, the combination with a main rheostat having resistor sections, and an auxiliary rheostat having a sectional resistor substantially equivalent to one section of the resistor of 10 the main rheostat, of means for operatively connecting said rheostats to cause the entire resistor of said auxiliary rheostat to be cut into or out of circuit while said main rheostat is varied by one resistor section, said 15 means comprising a pawl operatively connected to the auxiliary rheostat, a ratchet operatively connected to the main rheostat and means for rendering said pawl operative at predetermined intervals.
- 20 2. In an electric regulating switch, the combination with a plurality of stationary contact members, and a plurality of movable contact members for coacting therewith, of means for causing a uniform movement 25 of one of said movable contact members to intermittently actuate another of said movable contact members, said means comprising a pawl operatively connected to the auxiliary rheostat, a ratchet operatively connected to the main rheostat and means for rendering said pawl operative at predetermined intervals.
- 30 3. In an electric regulating switch, the combination with a plurality of stationary contact members, and a plurality of movable 35 contact members for coacting therewith, of means for causing a movement of one of said

movable contact members when another movable contact member has been actuated to a predetermined position, said means comprising a pawl operatively connected to the auxiliary rheostat, a ratchet operatively connected to the main rheostat and means for rendering said pawl operative at predetermined intervals.

4. In an electric regulating switch, the combination with a main rheostat comprising a pair of sets of contact members, the contact members of said sets being arranged in staggered relation the one to the other, 45 and a pair of contact arms for coacting with said contact members, of an auxiliary rheostat, and means for operatively connecting said rheostats to change the electrical connections of one of said arms upon the completion of a cycle of operation of the auxiliary rheostat.

5. In an electric regulating switch, the combination with a main rheostat and an auxiliary rheostat, of means for intermittently operatively connecting said rheostats, 50 said means comprising a pawl-and-ratchet mechanism and a member for retaining said pawl in an inoperative position except upon the completion of a cycle of operation by the auxiliary rheostat.

In testimony whereof, we have hereunto subscribed our names this 9th day of February, 1914.

LEONARD MILLER.
LAWRENCE BOOTHMAN.
